Primary Examiner—Joel Sincavage*Attorney, Agent, or Firm*—Quarles & Brady[57] **CLAIM**

The ornamental design for a shelf support and electrical cable management structure, as shown and described.

DESCRIPTION

FIG. 1 is a perspective view taken from the top, front and left side of a shelf support and electrical cable management structure embodying our new design;

FIG. 2 is a front elevational view thereof;

FIG. 3 is a right side elevational view, the left side being the mirror image of the right side;

FIG. 4 is a top plan view thereof;

FIG. 5 is a rear elevational view thereof;

FIG. 6 is a perspective view taken from the top, front and left side of a second embodiment of our new design;

FIG. 7 is a front elevational view thereof;

FIG. 8 is a right side elevational view thereof, the left side being the mirror image of the right side;

FIG. 9 is a top plan view thereof;

FIG. 10 is a rear elevational view thereof;

FIG. 11 is a perspective view taken from the top, front and left side of a third embodiment of our new design;

FIG. 12 is a front elevational view of the embodiment of FIG. 11;

FIG. 13 is a right side elevational view thereof, the left side being the mirror image of the right side;

FIG. 14 is a top plan view thereof;

FIG. 15 is a rear elevational view thereof;

FIG. 16 is a perspective view taken from the top, front and left side of a fourth embodiment of our design, of which the front elevational view is FIG. 7 and the rear elevational view is FIG. 10;

FIG. 17 is a right side elevational view of the embodiment of FIG. 16, the left side being the mirror image of the right side;

FIG. 18 is a top plan view thereof;

FIG. 19 is an enlarged view of the detail circumscribed by line 19—19 of FIG. 11; and,

FIG. 20 is an enlarged view of the detail circumscribed by line 20—20 in FIG. 10.

The broken lines in FIGS. 1, 2, 5, 6, 7, 10, 11, 12, 15 and 16 represent a continuous array of the opening shown with which they are aligned.
